UNITED STATES PATENT OFFICE.

JOHN B. MACNEILL AND JAMES M. BROWN, OF PITTSBURGH, PENNSYLVANIA, ASSIGNEES TO WESTINGHOUSE ELECTRIC & MANUFACTURING COMPANY, A CORPORATION OF PENNSYLVANIA.

DISCONNECTING SWITCH.

Application filed October 8, 1919. Serial No. 329,211.

Our invention relates to disconnecting switches, having special relation to switches used for breaking heavy currents, and it permits these switches to operate surely and 5 positively, with no accidental displacement of the parts.

More particularly, our invention relates to disconnecting switches comprising petticoat and pin-type insulators and to means for insuring 10 the accurate engagement of the knife blade with the break jaws.

Heretofore, in using disconnecting switches comprising petticoat and pin-type insulators, the hinge-jaw clamps have been 15 found to have a tendency to rotate on the axes of the insulators to which they were fastened. This rotation of the hinge-jaw clamp caused the knife blade to be thrown out of alignment with the break 20 jaws, and, consequently, the blade and break jaws would not engage when the movement of the former to circuit-closing position was attempted.

An object of our invention is to provide 25 a structure in which rotative movement of the hinge jaw clamp is rendered impossible and, at the same time, the construction is simple and durable.

With these and other objects in view, 30 which may be incident to the use of the improvements, the invention consists in the parts and combinations thereof hereinafter set forth and claimed, with the understanding that the several necessary elements constituting the same may be varied in proportions 35 and arrangement without departing from the spirit and scope of the invention.

In order to make the invention more clearly understood, we have shown, in the accompanying drawings, means for carrying the same into practical effect without limiting the improvements, in their useful applications, to the particular constructions, which, for the purpose of explanation, have been 45 made the subject of illustration.

Figure 1 is a top plan view of one form 50 of a switch embodying our invention; Fig. 2 is a side elevation of the switch shown in Fig. 1; Fig. 3 is a top plan view of a modification of the switch shown in Figs. 1 and 2, and Fig. 4 is a side elevation of the modification shown in Fig. 3.

Referring to Figs. 1 and 2, 1 indicates a 55 baseboard on which are mounted, by bolting or other suitable means, a plurality of in-

sulators 2, 3 and 4 of the well known petticoat and pin-type. Terminals 5 and 6 constitute means for connecting the main-line conductors to the switch.

Extending from the insulator 4 to the insulator 3 is a connecting bar 7 made integrally with an upstanding hinge-jaw clamp 8, which is located at one end thereof, and is suitably slotted for receiving one end of a knife blade 10. The knife blade 10 is pivotally mounted, at one end, on a bolt 9 that extends through the above mentioned slot. One end of the bar 7 is firmly bolted to the top of the insulator 4 and its other end to the top of the insulator 3. The terminal 5 is bolted, with the bar 7, to the insulator 4. To the top of the insulator 2 are bolted the terminal 6 and a break jaw 11, suitably slotted to receive the free end of the knife blade 10.

The knife blade 10 is provided with an aperture 10a near its point of engagement with the break jaw 11, which permits operation of the switch by means of a hook or any other proper instrument.

In Figs. 3 and 4, the support, comprising the two insulators 3 and 4 for the hinge jaw clamp 8 of the switch, is arranged at right angles to the longitudinal center line of the switch. The insulators 3 and 4 are connected by the connecting bar 7, which is suitably bolted to their tops. The hinge-jaw clamp 8 is formed integrally with the bar 7, with the slot for the reception of one end of the knife blade 10 at right angles to the axis of the bar 7. Formed integrally with the bar 7, and adjacent to the hinge jaw clamp 8, is an extension 12 which projects horizontally at both sides of the bar 7 and to which the conductor terminal 5 is bolted.

From the foregoing description, it is apparent that, by reason of the hinge jaw clamp 8 and the connecting bar 7 being formed integrally, there can be no relative movement between them. The connecting bar 7 is always mounted between the two insulators 3 and 4 and so cannot suffer displacement or rotative movement. As long as the insulators supporting the connecting bar 7 remain in place, the knife blade 10 will always move in the same plane to engage accurately, on the closing of the switch, with the break jaw 11.

Although we have shown and described our invention as applied to a specific struc-

ture, such as a disconnecting switch, it is evident that it may be applied to many other types of apparatus, and that various modifications may be made therein without departing from the spirit and scope of the appended claim.

We claim as our invention:—

10 A supporting member for a disconnecting switch comprising a metallic strip, oppositely extending ears located at the center of said strip for attaching an electrical con-

ductor, a pair of bosses for securing a switch member extending from a face of said strip in alinement with said ears, the ends of said strip being provided with securing means 15 for said strip.

In testimony whereof, we have hereunto subscribed our names this 30th day of Sept., 1919.

JOHN B. MacNEILL.
JAMES M. BROWN.
